(57) **CLAIM**

The ornamental design for a multi-player nine square, three-dimensional game, as shown and described.

DESCRIPTION

FIG. 1 is a perspective view of a multi-player nine square, three-dimensional game of our new design.

FIG. 2 is a front elevational view of the game of FIG. 1, each of the rear elevational view, the right side elevational view and the left side elevational view being the same as the front elevational view.

FIG. 3 is a top plan view of the game of FIG. 1.

FIG. 4 is a bottom plan view of the game of FIG. 1.

FIG. 5 is an expanded view of a portion of FIG. 1 illustrating a top corner intersection of the game FIG. 1.

FIG. 6 is an expanded view of a portion of FIG. 1 illustrating a top side intersection of the game FIG. 1.

FIG. 7 is an expanded view of a portion of FIG. 1 illustrating a top interior intersection of the game FIG. 1; and,

FIG. 8 is an expanded view of a portion of FIG. 2 illustrating a telescoping leg of the game FIG. 1.
